SIDE-STRIPPING CARTRIDGE BELT LINK

Russell Fagerberg and Keith Miller, Rockford, Ill., assignors to the United States of America as represented by the Secretary of the Army

Application March 11, 1955, Serial No. 493,841

2 Claims. (Cl. 89—35)

The invention relates to disintegrating ammunition belts for firearms and more particularly to belts adapted for use in feeding mechanisms of the type which extract each cartridge from the link associated therewith in a direction substantially at right angles to the longitudinal axis of the link.

As a result of the tortuous paths imposed on ammunition belts by the shortage of space frequently encountered between the source of the ammunition and the feeding mechanism of the firearm in many of the mounting arrangements in aircraft or tanks, it is essential that each link in the belt provide an extremely close grip on the cartridge associated therewith in order to prevent premature disengagement. However, present day cartridges are ordinarily formed with an appreciable forwardly converging taper on the case portion thereof, especially in the larger calibers. Consequently, the desired gripping relationship between each link and cartridge necessitates a smaller loop at the front end of the link than at the rear end thereof. Such design obviously does not lend itself to the push-through method of extracting a cartridge from the link associated therewith, commonly referred to as "stripping" and, therefore, has been eliminated in many instances in favor of a link from which the cartridge is laterally stripped by suitable wedging fingers included in the feed mechanism of the firearm.

While the use of the latter type of link has successfully eliminated the stripping problem created by appreciable taper in the cartridge case, the fact that the cartridge is forced out from between the open end portions of each cartridge-gripping loop necessarily limits the circumferential extent thereof. The resulting increased space between the terminal ends of the loops introduces the possibility of relative longitudinal movement between the cartridge and its link in response to the repeated flexure and twisting forces imparted to the ammunition belt during the feeding travel thereof. Attempts to prevent such link movement, commonly called "walk-out," have invariably resulted in an appreciable increase in both the length and weight of the link.

Accordingly, it is an object of this invention to provide a compact side-stripping type of cartridge belt link having improved cartridge-gripping characteristics which do not depend on any increase in the size and weight of the link itself.

One of the requisites for providing an adequate gripping relationship between a cartridge belt link and the cartridge associated therewith is the resiliency of the material from which the link is fabricated. However, any increase in the resiliency of the link permits a corresponding increase in the amount of helical twist which can be imparted to the ammunition belt. While a limited amount of helical twist between adjacent links is required to enable the ammunition belt to follow the circuitous path formed between the various guides and rollers included in conventional ammunition boxes and chutes, excessive helical twist permits such change in direction of the exposed portion of the ammunition belt between the fire-

2

arm and the end of the feed chute that the leading cartridge often fails to enter into the feeding entrance of the firearm. Prior art attempts to limit excessive helical flexibility of the belt were invariably accompanied by a corresponding decrease in the flexibility of each link which consequently reduced the cartridge-gripping ability thereof.

Another object of this invention, therefore, resides in the provision of an improved connection between adjacent cartridge belt links wherein the helical flexibility of the ammunition belt formed thereby is positively restrained after a predetermined amount of free movement without the necessity for increasing the rigidity of each link.

Still another object of this invention is to provide an improved means for connecting adjacent cartridge belt links so that a limited amount of free helical flexibility therebetween will not be continued as strained helical flexibility despite the increase in the twisting forces being applied thereto.

It is a specific object of this invention to provide a side stripping cartridge belt link having a structure of superior flexibility which nevertheless is compact, sturdy and light in weight.

The specific nature of the invention as well as other objects and advantages thereof will clearly appear from a description of a preferred embodiment as shown in the accompanying drawings in which:

Figure 1 is a left-side view of the link with a cartridge engaged thereby;

Figure 2 is an enlarged bottom view of the cartridge belt link of the present invention;

Figure 3 is an enlarged end view looking at the front end of the link;

Figure 4 is an enlarged perspective view of the link connector; and

Figure 5 is an enlarged side view showing the manner in which the connector prevents restrained flexibility between adjacent links.

As shown in the drawings, each link is formed as a unitary member which comprises open front and rear arcuately formed cartridge-gripping loops 12 and 13, respectively, which are joined by a bridge portion 14 having centrally-disposed, oppositely-projecting arms 15. The contour of arms 15 is such as to form a substantially elliptical loop 16 which projects beyond the peripheries of loops 12 and 13 and serves as part of the means through which each link is articulately connected to the one adjacent thereto. The exterior periphery of loop 16 is depressed to form a substantially rectangular rib 17 which blends into the interior peripheries of arms 15 for increasing the stiffness thereof. Loop 12 is provided with oppositely disposed detents 18 adjacent the terminal ends thereof which are arranged to grip a cartridge 19 at the crimping groove 20 employed to hold projectile 21 in the case 22. Loop 13 is slightly larger than loop 12 in view of the increased diameter of case 22 at the area at which such loop is intended to engage. The resiliency of loops 12 and 13 is increased by the removal of substantial portions of metal therefrom at the junction with both arms 15 as best shown at 23.

The exterior arcuate edges of loops 12 and 13 are cut away, to form oppositely converging parallelogram sections 24 on either side of bridge portion 14. The angular sides of the tongues 25 left between sections 24 serve to receive the camming thrust of suitable stripping mechanism (not shown) by means of which cartridge 19 is forced downwardly out between the open ends of loops 12 and 13. In order to facilitate the entry of the stripping members (not shown) into the parallelogram-shaped cut-out sections 24, the outer corners 26 thereof are bent inwardly toward one another as best shown in Figure 3.

65

70

Accordingly, tongues 25 need not extend beyond the configuration of the link itself and consequently such configuration aids considerably in effecting the desired compactness of structure.

Adjacent links are joined to one another by means of a substantially rectangular connector 27 having a rectangular opening 28 arranged to loosely receive one arm 15 on each link. However, after one of arms 15 is inserted through connector opening 28 the corners of the terminal end of such arm are flattened as shown at 29 so as to extend outwardly and permanently retain connector 27 thereon. The terminal end of arm 15 on the second link is, of course, left untouched to permit the necessary disintegration between adjacent links during their passage out of the firearm. The opposite ends of connector 27 are bent downwardly and inwardly toward one another as shown at 30 in Figure 4 whereby the oppositely-facing terminal edges are in substantial vertical alignment with the respective ends of opening 28. Since the length of opening 28 is slightly larger than the width of arms 15, the twisting of one link relative to the one adjacent thereto is freely permitted until positively limited by the contact between the edges of the curved ends 30 of connector 27 and the peripheral edges on the sides of arms 15 as best shown in Figure 5. Due to the inherent strength in the design of ends 30, the foregoing structure prevents the strained helical flexibility ordinarily encountered between adjacent links with prior art types of independent connectors.

Since loop 12 engages the conventional crimping groove 20 in cartridge case 22, the link is positioned substantially at the center of gravity of cartridge 19 and, therefore, is not subjected to the excessive twisting forces normally encountered in those designs where the link grips the cartridge at the extractor groove in the rear end thereof. Consequently, the link of the present invention minimizes the tendency for the cartridge to move longitudinally relative thereto as a result of the flexing to which the ammunition belt is subjected during its feeding travel. Furthermore, this reduced tendency of the cartridge to "walk" relative to the link permits the relatively compact structure so essential where size and weight are important factors.

In addition, the curled ends of the present connector provide a substantially rigid structure for limiting the relative twisting between adjacent links after a predetermined amount of unopposed or free flexibility. In prior art links, the connectors merely resisted the relative twisting between adjacent links and, therefore, were also twisted to some degree when an unusual amount of force was encountered.

Although a particular embodiment of the invention has

been described in detail herein, it is evident that many variations may be devised within the spirit and scope thereof and the following claims are intended to include such variations.

We claim:

1. A cartridge belt link of the type from which the cartridge is laterally stripped comprising a longitudinal bridge portion, a pair of open arcuate cartridge-gripping loops depending from the front and rear ends of said bridge portion, said front loop being of slightly smaller diameter than said rear loop and having opposed detents adjacent the terminal ends thereof and adapted to engage at the front end of the cartridge case, a substantially rectangular arm curving outwardly from either side of said bridge portion centrally of said loops to form an open elliptical section, said bridge having spaced apart cutaway portions defining tongue-like projections at either end thereof, the outer corners left by said cutaway portions on said loops being bent inwardly toward one another and away from said tongue-like projections to define a larger opening for effecting easier stripping of the cartridge, and a substantially rectangular connector having a substantially rectangular opening for loosely receiving the terminal ends of said rectangular arms on adjacent links, one of said terminal ends having outwardly flaring corners for permanently but loosely retaining said connector thereto.

2. A cartridge belt link of the type from which the cartridge is laterally stripped, comprising a longitudinal bridge portion, a pair of open arcuate cartridge-gripping loops depending from the front and rear ends of said bridge portion, said front loop being of slightly smaller diameter than said rear loop and arranged to grip a cartridge case at the front end thereof, a substantially rectangular arm curving outwardly from either side of said bridge portion centrally of said loops to form an open elliptical section projecting outwardly beyond the periphery of said cartridge-gripping loops, and a substantially rectangular connector having a substantially rectangular opening therein for loosely receiving the terminal ends of said rectangular arms on each of two adjacent links, one of said adjacent terminal ends having outwardly flaring corners for permanently but loosely retaining said connector thereon, said connector having opposite inwardly curled ends adapted to contact the sides of said rectangular arms extending therethrough for positively limiting any additional helical twisting between adjacent links.
